UNITED STATES PATENT OFFICE.

JOHN C. NOEL AND GEORGE PARTON, OF LONGMONT, COLORADO, AS
SIGNORS OF ONE-THIRD TO WILLIAM H. WALKER, OF SAME PLACE.

COMBINED WHEELED HARROW AND SEEDER.

SPECIFICATION forming part of Letters Patent No. 369,072, dated August 30, 1887.

Application filed March 9, 1887. Serial No. 230,195. (No model.)

To all whom it may concern:

Be it known that we, JOHN C. NOEL and GEORGE PARTON, of Longmont, in the county of Boulder and State of Colorado, have invented certain new and useful Improvements in Combined Wheeled Harrows and Seeders, of which the following is such a full, clear, and exact description as will enable others skilled in the art to which it pertains to make and use the same.

The objects of our invention are to improve the mechanism for raising and lowering the harrow in sections or as a whole, either to avoid obstructions while in use or to readily transport it from place to place, to make it convenient to turn, on a short space, to operate the seeder from one wheel of the carriage, and to otherwise improve the usefulness of such devices.

20 The invention consists in certain features of construction and combination, hereinafter specifically set forth.

In the two sheets of drawings, forming part of the specification, and in which the same or 25 corresponding parts are denoted by the same reference-characters, Figure 1 is a perspective view of our invention. Fig. 2 is a plan view of the same. Fig. 3 is a view of the front pulley-shaft and its pulleys. Figs. 4, 5, and 30 6 are details of the parts shown in Fig. 3. Fig. 7 shows the three-part rear pulley-shaft and its pulleys.

Referring by characters to the drawings, A 35 A A A represent the wheels; b, the carriage having the offset at b', for the purpose of allowing the fore wheels to pass freely under the front elevated part of the carriage, thus allowing the whole to be turned short and on a small space of ground.

40 B' denotes the front bolster, to which the harrows B B B are secured by means of the chain C C and the intermediate bar or rail, A'. The usual clevises are used.

C' is the seeder or grain-box, located just 45 back of the offset in the carriage. Within this box is a rotary stirrer-shaft, E'', on one end of which is mounted a sprocket-wheel, E'. About this sprocket-wheel E' and the sprocket-wheel E on one of the rear wheels passes the 50 sprocket-chain or suitable band, D. The operator's seat is secured to the front bolster, B'.

Mounted in bearings on the fore part of the carriage b is a pulley-shaft, d, whose main portion is square or angular. It is round within its bearings and at the portions where the pulleys e e are mounted, as plainly seen in Fig. 3; hence these pulleys turn freely in one direction on the said shaft, and would turn freely in the other direction were it not for the cams i' i', attached firmly to the said shaft or being a part thereof, one at one side of each of said pulleys e e, and the pawls i i, one of which is attached to each of said pulleys. The pulley e' is secured on the angular part of this shaft, and hence this pulley and the shaft turn together. Attached to each pulley e is a lever, H, and a lever, H', is attached to the pulley e'. These handles or levers H H' are readily within reach of the driver when seated on the seat. Attached to each pulley e e is a chain, e'', and to the pulley e' a chain, e''. These chains are secured within a groove in the periphery of their respective pulleys by means of a staple or otherwise. Each chain e'' e'' e''' runs back 75 over the frame b, and is attached within the groove of a pulley, F', which is secured at or near one end of the pulley-shaft F. At the other end of each shaft F is a pulley, F''. These pulleys F' F'' are rigidly secured on the 80 shafts F.

The shafts F may be made angular at all parts except at their bearings on the frame B, or the pulleys may be splined on the shafts. As seen in Fig. 7, there are three sections of 85 pulley-shafts, F F F. There are also three sections of harrows, B B B, shown, or three separate harrows. The number of pulley-shaft sections and the harrow-sections are the same.

Each chain e'' e'' e''' passes over and partly 90 around its corresponding pulley, F' F' F', to which it is secured by a staple or some suitable means. In the peripheral groove of each pulley F'' F'' F'', secured on said shaft F F F, is secured a chain, G G G, which passes forward toward the center of its corresponding harrow-section, B, to which each said chain is secured by means of a hook, staple, or any other convenient means. Alongside of the lever H', which is attached to the pulley e', is 95 a toothed rack, H'', whose teeth point forward, so that the sharp edge of the lever H' can be 100

caught and held off any one of these teeth, for a purpose hereinafter stated.

The operation of our combined harrow and seeder is as follows: When the machine is put 5 in motion by means of horses harnessed to it in the usual manner, the sprocket-chain D is put in operation by the sprocket-wheel mounted on the hub of one of the wheels of the carriage. The sprocket-wheel operates the stirrer or seed-10 scatterer within the seed-box, and thus properly distributes the grain upon the ground just in front of the harrows. The harrows, following, properly cover up the seed. Suppose there is an obstruction in advance of one or 15 the other side of the harrow. The driver will grasp in his hand the lever H of the harrow-section, which he may wish to lift to clear the obstruction, and since the pulleys e turn freely on the shaft, as he lifts, the said pulley will 20 turn, the pawl i receding or moving away from the shoulder or cam i'. These pulleys e e' we preferably make about twelve inches in diameter; hence one-half a revolution of the pulley will lift up its harrow-section B about eighteen 25 inches, so as to clear quite a high obstruction; and as the pulley-shafts F F' F are three separate independent shafts, the raising of a lever, H, will raise but one section B; but suppose it is desired to pass a large obstruction, or to 30 remove the combined machine from field to field or from farm to farm, and it is desirable that the harrows shall not drag on the ground. The driver in that case lifts the handle or lever H', which is secured to the pulley e'. Now, as 35 has been stated, this pulley is rigidly attached to its shaft d; hence turning the pulley also rotates its shaft, and as the shaft d commences to rotate forward, the cams i' lock against the pawls i on the pulleys e, and thus lock these 40 pulleys to the said shaft, and so all of the harrow-sections are raised through the chains e'' e''' G G G simultaneously. As the lever H' can be caught in the rack H'', the driver is relieved of the burden of holding it.

45 Having thus described our invention, what we desire to secure by Letters Patent of the United States is—

1. The combination of a wheeled carriage, a seeder mounted thereon, a series of harrows 50 attached to the front bolster of said carriage, a front pulley-shaft, a rigid pulley and two loose pulleys mounted thereon, means to cause said loose pulleys to turn with said shaft, a sectional rear pulley-shaft, (each section carrying two pulleys,) a separate chain connecting each front pulley with one of each pair of

rear pulleys, another chain connecting each of the other rear pulleys to a harrow, two sprocket-wheels—one on the scatterer of said seeder, the other on the hub of one wheel of the carriage—and a sprocket-chain gearing said sprocket-wheels together, as and for the purpose set forth. 60

2. In a combined wheeled harrow and seeder, the combination of the carriage, the shaft d, the pulleys e e', the levers H H', the shafts F F' F and the pulleys F' F'', the chains e'' e''' G G G, and the harrows B B B, substantially as described. 65

3. In a combined wheeled harrow and seeder, the combination of the carriage, the shaft d, having cams i, with pulleys e e, having the pawls i i, the pulley e', the rear pulley-shaft having the rigidly-attached pulleys F' F'', the harrow-sections B B B, and the chains e'' e''' G G 75 G, all substantially as described. 70

4. The combination of the carriage b, having the offset U', the front pulley-shaft and its pulleys, one being rigidly fixed thereon, the others being capable of free rotation thereon, 80 but also capable of being locked to the shaft when the shaft itself is rotated, the separate rear pulley-shafts and the pulleys mounted thereon, the chains intermediate these two sets of pulleys, the harrow-sections, chains 85 connecting the harrows and the last said pulleys, and means for operating the front pulleys, as described. 90

5. In a combined wheeled harrow and seeder, the combination of a wheeled carriage having an offset, a seeder-box, a stirrer in said box carrying a sprocket-wheel, a sprocket-wheel on one wheel-hub, a sprocket-chain passing around these two sprocket-wheels, a front pulley-shaft, a set of pulleys on said shaft, a rear 95 pulley-shaft made in sections, as many harrow-sections as there are sections in the pulley-shaft, chains connecting these harrows and pulley-sections and chains connecting the two sets of pulleys, and means for lifting the harrow-sections both separately and all together, 100 as described.

In testimony that we claim the foregoing as our invention we hereby sign our names, this 28th day of February, 1887, in the presence of 105 two witnesses.

JOHN C. NOEL.
GEORGE PARTON.
